MATERIAL APPLICATOR FOR PLANO-
GRAPHIC PRINTING MACHINESFranklin E. Curtis, Willoughby, Ohio, assignor
to Addressograph-Multigraph Corporation,
Cleveland, Ohio, a corporation of Delaware

Application November 13, 1937, Serial No. 174,396

17 Claims. (Cl. 101—148)

This application is a continuation in part of my copending application for Letters Patent, Serial No. 147,507, filed June 10, 1937. The present invention is especially concerned in and to improvements in printing or duplicating machines, of the planographic type, and more particularly to an improved material applicator system for a planographic printing machine. The present invention includes both an improved ink applicator and an improved repellent applicator. These, therefore, are the general objects of the present invention.

An object of this invention is the provision of an improved compact, planographic duplicating machine, especially adaptable for general office work, which is simple in operation and will require but a minimum amount of attention by the operator, to the end that comparatively unskilled operators may successfully operate the machine over continuous periods of time.

A more specific object of the present invention is the provision of a material applicator system, including an ink applicator and a repellent applicator, which applicators will be simple in operation and so arranged that they will require a comparatively minor adjustment, to the end that they may be controlled in a simple manner to facilitate use of the machine by comparatively unskilled operators.

Another object is to provide an improved doctor roll mounting and driving mechanism for a material applicator, which will enable an exceedingly even application of fluid material to the printing plate while maintaining the number of material transfer elements, such as rollers, to a minimum.

Other objects of the present invention will become more apparent from the following description, reference being had to the accompanying drawings, in which there is illustrated a preferred embodiment of the invention. The essential features of the invention will be summarized in the claims.

In the drawings, Fig. 1 is a substantially centrally located longitudinally extending section through a printing machine embodying my improved material applicator system; Fig. 2 is a plan view of the machine, partially broken away, to more clearly illustrate the internal construction of the mechanisms; Fig. 3 is a fragmentary side elevation of the machine, looking in the same direction as in Fig. 1, with the side cover plate removed and certain other parts broken away to more clearly illustrate the operating and control mechanism for the material applicator system; Fig. 4 is a fragmentary sectional view taken on

the line 4—4 of Fig. 3, and illustrates an improved form of mounting for certain of the rollers of the material applicator system; and Fig. 5 is a fragmentary sectional view taken on the line 5—5 of Fig. 1.

In the drawings I have illustrated my improved material applicator system in a planographic printing machine of the type shown and described in my copending application heretofore referred to. In the present application this printing machine has been simplified in many details for ease of illustration. However, reference may be had to the copending application, referred to, for a more complete disclosure of such machine. In the drawings of the present application there is shown a frame, comprising a pair of slide plates 11 and 12, tied together by suitable cross members, some of which are generally indicated at 10. Rotatably journaled in this frame are a pair of horizontally extending shafts 15 and 16, 20 the former supporting a transfer roll 18 and the latter a pattern roll 19, which carries a printing member B. The shafts 15 and 16 are preferably mounted in eccentric bushings, 16a in the well known manner, to permit them to be adjusted and 25 aligned, one with the other. Rotatably journaled on a shaft 20, below the transfer or offset cylinder 18, is a platen roll 21. The platen roll shaft 20 may be supported by the frame members 11 and 12 in a manner to permit adjustment and 30 alignment of the roll with the offset cylinder. A suitable sheet feed table 22 is mounted on the frame to enable work sheets to be fed into the bite of the platen and offset rolls 21 and 18, respectively.

The offset roll may be provided with a suitable gripper and ejector mechanism, illustrated in my copending application, heretofore mentioned, to receive the paper sheet ahead of the bite of the printing couple and eject or strip such sheet 40 from the roll following the passing of the paper between the printing couple, guiding such printed sheet beneath a paper guide 23 into a suitable receptacle or receiving hopper 24 carried by the frame.

The present invention is especially concerned with the material applicator system for first applying an ink repellent to the planographic or similar type of printing plate, and subsequently applying planographic ink to such repellent coated plate, so that only the image portions of the printing plate will carry ink to the transfer roll 18, therefore to the work sheet.

The moistening or ink repellent fluid is stored in a removable fountain or tray 30, which is sup- 55

ported on lugs or ears 31 extending from the frame plates 11 and 12. This fluid is removed from the fountain 30 by a fountain roll 32. The fountain roll is drivingly mounted on stub shafts 33, which are journalled in respective frame plates 11 and 12. This roll is intermittently driven, as will be hereinafter described.

The moistening or repellent fluid is transferred from the fountain roll 32 to a form roll 34 by a ductor roll 35. The ductor roll 35 is rotatably mounted on a shaft 36, supported by upstanding arms of a yoke 37. This yoke is pivotally secured to a second yoke 38, the downwardly depending arms of which are pivotally mounted on respective frame members 11 and 12, as at 39. This pivotal connection and its advantages will be hereinafter more fully described. The ductor roll 35 is intermittently rocked from contact with the fountain roll 32 into contact with the form roll 34, as will be hereinafter explained.

The form roll 34 of the moistening or repellent mechanism is rotatably mounted on a shaft 40, carried between a pair of arms of a yoke 41, which arms are pivoted to the respective frame members 11 and 12, as indicated at 42 in Fig. 1. The form roll is resiliently maintained in contact with the printing plate B, by suitable springs, one of which is shown at 43, as being interposed between the upper end of one arm of the yoke 41 and a pin 44 secured to the frame member 12. Adjusting screws, such as that shown in Fig. 1, at 45, are mounted in the form roll yoke arms 41 and contact fixed abutments 46 of respective frame members 11 and 12. Thus a predetermined pressure may be maintained between the form roll 45 and the pattern.

The form roll 34 and its carrier yoke 41 are removable as a unit from the machine. The springs 43 which retain the roll in contact with the pattern drum 19 are removed from the frame. Then one of the yoke pivot pins, as, for instance, the pin shown at 42 in Figs. 1 and 5, is disengaged from the yoke, permitting the yoke to be slid from engagement with the pin 42 on the other side of the machine, which latter named pin (not shown) is rigidly secured to its frame member 11. The pin 42, illustrated, is slidably mounted in the frame plate 12 and is normally positioned in a suitable opening by a spring 46. A knob 47 is provided to facilitate the withdrawal of the pin.

Both the form roll 34 and the ductor roll 35 are provided with absorptive fabric coverings 47 to enable them to convey the fluid from the fountain roll to the printing plate.

Ink is supplied to the moistened pattern by an inking mechanism, best shown in Fig. 1. This inking mechanism comprises the usual fountain 50 carried by the frame members 11 and 12. This fountain is provided with a fountain roll 51, against which the usual fountain plate 52 is adjustably positioned by a plurality of adjusting screws, one of which is shown in Fig. 1 at 53. Ink is transferred from the fountain roll 51 to a transfer roll 54 by a ductor roll 55. This ductor roll is rotatably mounted on a shaft 56, supported by a pair of upstanding arms of a yoke 57. This yoke is pivotally secured as at 58, as will be hereinafter more fully described, to a second yoke 59, the depending arms of which are pivotally secured to respective frame members 11 and 12, as at 60. The ductor roll is rocked periodically about the pivots 58 into alternate engagement with the fountain roll and the trans-

fer roll, by mechanism to be hereinafter more fully described.

The ink transfer roll 54 is journalled on a shaft 61. This transfer roll transfers the ink from the ductor roll 55 to a form roll 62, which is journalled on a shaft 63. The ends of this shaft are mounted in slots 64 formed in respective bracket members 65, one of which is shown in Fig. 1. These bracket members are pivotally secured to respective frame members 11 and 12 by pivot pins 66, and are normally rocked about their pivots, to draw the form roll 64 into contact with the pattern or printing plate, by a pair of springs, one of which is shown at 67 in Fig. 1. One end of each spring 67 is secured to its respective bracket as at 68, while the other end is carried by a hooked plate 69 having an enlarged opening 72 through which a frame pin 70 extends. This facilitates the disconnection of the spring and thus the rocking of the brackets outward to enable the form roll to be removed.

The pressure of the form roll 62 against the pattern B is limited by a pair of set screws, which are mounted in the respective bracket members 65. One of these set screws is illustrated at 71 in Fig. 1, as being threadingly mounted in an ear 72 formed in the bracket and engaging a boss 73 of the adjacent frame member 11 or 12. A suitable lock nut 74 is provided to lock the set screw 71 in an adjusted position.

The ink distributor roll 54 is driven in synchronism with the pattern drum 19. As indicated in Fig. 1, a gear 85 is drivingly secured to the pattern drum and meshes with a pinion 85 which in turn drives a gear secured to the distributor roll 54. The drum 19 is driven from a motor M, the driven pulley 87 of which is connected with a pulley 88 by a drive belt 89. The pulley 88 is secured to a stub shaft 90, journalled in the frame plate 12. Also drivingly secured to this stub shaft is a spur gear 91, which meshes with a gear 92 of a compound gear member rotatably mounted on a stud 93. The other gear 94 of this gear member meshes with and drives the spur gear 95, heretofore described, as being drivingly connected to the pattern drum 19, as well as to the distributor roll 54.

The ink fountain roll 51 is driven from a cam 100 mounted on the transfer roll 54, which, in turn, is driven by the pattern drum gear 85 through a gear 101. Thus, when for any reason the transfer and pattern drums are separated, as, for instance, by the rotation of their eccentric bushings 102, the ink supply to the pattern will, for practical purposes, cease. As indicated in Fig. 1, the offset roll is provided with a cam 100, having a cam groove 102, into which a roller 103 projects. This roller is carried by a lever 104 secured to a rock shaft 105, which is journalled in the frame member 11. Also secured to this rock shaft 105 is an arm 106, which is pivotally connected, as at 107, to one end of a link 108. As shown in Fig. 3, a pawl formation 109 is secured to the other end of the link 108. This pawl formation is adapted to engage a ratchet wheel 111, secured to the outward projecting end of a shaft 112, journalled in the end plates of the ink fountain and to which the fountain roll 51 is secured. Thus, the fountain roll is advanced a partial revolution each time the link 108 is reciprocated by the cam 100.

The ductor roll of the ink repellent applicator is likewise driven by the offset roll 18. As shown in Fig. 3, a second arm 113 is secured to the rock 75

shaft 105, which, as heretofore described, is rocked by the cam 100 of the offset roll 18. This arm 113 is connected by a link 114, with a plate 115, which is pivotally mounted on the ductor roll shaft 33 of the repellent applicator. Pivoted to the plate 115, as at 117, is a pawl 116, which, by means of a spring 118, is normally maintained in engagement with a ratchet wheel 119 drivingly mounted on the ductor roll shaft 33, heretofore described. Thus the ductor roll 32 is advanced step by step as the offset drum 18 is rotated.

An adjustment is provided whereby the pawl 116 may be regulated to advance the ratchet wheel, and therefore the fountain roll 32, a distance equivalent to a selected number of ratchet teeth, for each revolution of the offset drum 18. This adjustment, as shown in Fig. 3, is accomplished by positioning a cam plate 120 about its axis, the fountain roll shaft 33 causing the cam portion 121 of the plate to engage a pin 122 carried by the pawl 116. This disengages the pawl from the ratchet wheel at a predetermined point, thus determining the distance the ratchet wheel is to be advanced. A suitable detent, such as the spring 123, engages one of a plurality of notches 124 in the cam plate to maintain it in an adjusted position. An extension 128 of this cam plate may project through the frame and cover plates to facilitate the manipulation of the cam. If desired, a similar arrangement may be used to regulate the feed of the ratchet 111 of the ink fountain roll 51, heretofore described.

The ductor rolls 35 and 55 are swung between their respective fountain and form rolls by the links 108 and 114 of their respective applicator mechanisms, and hence by the rotation of the offset printing drum 18.

The driving connection between each of the links 108 and 114 and its respective ductor roll is such that the ductor rolls dwell in their movements to contact with their respective fountain and form rolls for a period of time. In the case of repellent ductor roll 35, one of the depending arms of the supporting yoke 38 is provided with an upward extension, which is provided with a pin 130, which passes through a slot 131 in the driving link 114. Secured to the pin 130, and mounted at either side of the link 114, are friction discs 132. These discs are secured to the pin and frictionally embrace the link 114, so that, as the link moves to the left side (Fig. 3), the friction discs 132 and the pin 131 of the ductor roll mounting yoke 38 move with the link as a unit. When, however, the link has moved the ductor roll 35 into contact with the fountain roll 32, further movement of the rolls is, of course, restricted by such contact. The link then moves between the friction discs, thereby allowing the ductor roll to dwell in contact with the fountain roll until such time as the link 114 starts its right-handed movement (Fig. 3). On the reverse movement, the ductor roll similarly remains in contact with the form roll 34, for a like period of time.

The connection between the ductor roll 55 of the inking mechanism and the link 108, is also such that this ductor roll remains in contact with its fountain roll 51, and its distributing roll 54 for a considerable period of time. As shown in Figs. 3 and 4, one of the depending arms of the ductor roll supporting yoke 59 is provided with an upward extension 134 having a pin 135, which projects through the frame member 11, thence through an elongated opening 133 in the link 108, and into an opening 136 in a strip 137. The strip 137 is fric-

tionally carried by the link 108, being pressed between a pair of fibre strips 138 by compression springs 139, surrounding a pair of studs 140 carried by the link. These studs pass through an elongated slot 143 in the strip 137, allowing endwise motion of the strip with respect to the link. When the link 108 moves to the right (Fig. 3), the extension 134 of the yoke 59 and the ductor roll 55 are swung in a clockwise direction, bringing the ductor roll into contact with the fountain roll 51. This contact is maintained for an interval of time, due to continued movement of the link and slipping of the strip 137. When, however, the link moves to the left, the ductor roll is disengaged from the fountain roll and is moved into contact with the distributing roll 54. This contact is also maintained for an interval of time, due to the frictional engagement of the strip 137 with the link and is broken only when the direction of movement of the link is again reversed.

The ductor rolls of both applicator mechanisms are mounted to compensate for any irregularities in the alignment of the form rolls, the fountain rolls and the ductor rolls. This is highly advantageous in that it equalizes the pressure between all points of these rolls, thus transferring a very even coating of ink from the fountain roll to the form roll.

As both ductor rolls are mounted in the same manner, a description of the mounting for the ink fountain ductor roll 55 will suffice for both. As heretofore mentioned, this ductor roll is journaled in the upstanding arms of a yoke 57, which is carried by a yoke 59, the depending arms of which are pivoted to adjacent frame plates. As shown in Fig. 4, the yokes each have horizontal bar portions 145, which are pivotally connected together, as at 158, to swing about a substantially vertical axis midway between the arms of the yokes. Inasmuch as the lower yoke 59 is driven, the ductor roll is free to swing about its vertical pivot 58, into alignment with the fountain roll or distributor roll until the pressure between all contacting points of the contacting rolls is equalized. Excess pressure is, of course, prevented, due to the frictional drive between the link 113 and the yoke propelling plate 137.

When the machine is idle, it is desirable to move both the ink repellent form roller and the ink form roller out of contact with the pattern or printing plate. Again, at times it is desired to supply the repellent only, while at other times it is desirable to supply the printing plate with ink only. Therefore, there is provided a mechanism, about to be described, which may selectively move either or both of the form rolls out of contact with the pattern cylinder, as desired.

As shown in Figs. 1 and 3, a shaft 150 is journaled in the frame members 11 and 12, and on its outer end is provided a knob 151 to enable it to be readily grasped and turned by the operator. The knob is provided with a suitable pointer 152, which coacts with an index plate 153, secured to the frame of the machine, and which bears indicia indicating the position of the form rolls.

As shown best in Fig. 1, the shaft 150 intermediate its ends is provided with a cam-like formation 154, which is arranged to selectively engage the bracket members 65 carrying the ink form roll 64, and rock such roll about the bracket pivots, against the action of the springs 67, thereby moving the ink form roll out of contact with the printing plate B.

Secured to the shaft 150, as shown in Fig. 3, is a cam 146, and pivoted as at 149 to the frame 11

is a lever 148 having a cam engaging roller 147 on its lower end. The upper end of this lever has pivoted thereto a link or bar 151, which is guided in its movement by a pin 158, carried by the frame member 11 and projecting through a slot 159 formed in the bar 157. The left-hand end of this bar, as illustrated in Fig. 3, engages a lip 155 formed on one of the arms 141 of the repellent form roll supporting yoke 41. Consequent upon the rotation of the cam 146, the bar 157 will move the form roll 34, against the action of the spring 43 out of engagement with the printing plate B.

The formation of the cam 146 and the cam shaft 154 is such that, when the shaft is turned to the position illustrated in Fig. 3, both form rolls 34 and 64 are in contact with the printing plate B. As the cam is rotated from the "on" position, shown in Fig. 3, in a counter-clockwise direction to the position designed "Rep. only", the cam surface 154 acts to move the ink form roll away from the printing plate, thereby permitting the application of repellent only. Further movement of the shaft 158 in a counter-clockwise direction to the "off" position brings the cam 146 into action, moving the repellent application form roll also out of contact with the printing plate, thus positioning both form rolls free from the drum. Further movement of the shaft 158 in a counter-clockwise direction to the "ink only" position moves the cam shaft 154 out of active engagement with the brackets 65, thereby releasing the ink form roll for contact with the printing plate B, whereas the cam 146 remains active, retaining the repellent form roll out of contact with the printing cylinder. Thus the application of ink only to the printing cylinder is accomplished.

From the foregoing description, it will be seen that I have provided an efficient material applicator system for a planographic or similar printing machine, which system includes a liquid repellent applicator mechanism and an ink applicator mechanism, both of which mechanisms are driven from the offset or transfer roll, and each of which mechanism is arranged to facilitate the removal of the form rolls without disturbing their adjustment to other rolls in the inking system, and each of which includes a ductor roll which is pivotally mounted to align with either its fountain roll or its distributor roll, regardless of misalignment between the axes of the three rolls. This pivotal mounting, together with the frictional driving mechanism for oscillating the ductor rolls and causing them to dwell in contact with their fountain and distributor rolls, enables an even limited pressure between the contacting rolls and therefore transfers an even application of repellent or ink, as the case may be, to the printing plate. An improved simple control for the operation of both applicator mechanisms is also provided, thus facilitating the operation of a planographic printing machine by comparatively unskilled help, thereby providing a planographic printing machine for general office duplicating work.

I claim:

1. In a planographic printing machine, having a plate cylinder, an ink feed for the plate cylinder, a repellent feed for the plate cylinder, each of said feeds including a movable ductor, means for moving the ductors, said means including movable members frictionally connected with the ductors and arranged and adapted to permit the ductors to dwell in engagement with the mem-

bers against which they are moved while said movable members continue their movement.

2. In a printing machine, the combination of a plate cylinder, a form roll, a fountain roll, a movable ductor between the fountain roll and form roll, mechanism for operating the movable ductor comprising a movable bar having an elongated slot therein, means to reciprocate the bar, the ductor roll having a pin extending through the slot in the bar, and means connected with the pin to frictionally engage opposite sides of the bar and thus propel the ductor, and wherein said means is adapted to be overcome consequent upon the contact by the ductor roll of one of the other rolls.

3. In a planographic printing machine, the combination of a plate cylinder, an ink feed and a repellent feed for the plate cylinder, each of said feeds including a movable ductor roll, two reciprocating bars having yielding connections with the two ductor rolls respectively, and single means for operating the two bars.

4. In a planographic printing machine, the combination of a plate cylinder, an ink feed and a repellent feed for the plate cylinder, each of said feeds including a movable ductor roll, movable members having yielding connections with the two ductor rolls respectively, a rock shaft, rock arms on the rock shaft, connected with the respective members, and a cam for operating the rock shaft.

5. The combination, with a rotatable movable fountain roll and a bodily movable ductor roll, of a single driver for both movements, and mechanism connecting the driver with the two rolls, said mechanism having a frictional connection with the ductor roll whereby the ductor roll may dwell at one end of its movement while the mechanism continues to operate the fountain roll.

6. In a material applicator for a printing machine, the combination of a rotatable fountain roll, a bodily shiftable and rotatable ductor roll, a common driving mechanism for rotating the fountain roll and shifting the ductor roll, said mechanism having a frictional slip connection with the ductor roll, and a positive connection with the fountain roll, whereby the ductor roll may dwell in contact with the fountain roll while said mechanism continues to rotate the fountain roll, and thereby causes the ductor roll to be rotated by frictional engagement with the fountain roll.

7. In a planographic printing machine, the combination of a plate cylinder, a form roll adapted to coast therewith, a fountain roll, a bodily shiftable and rotatable ductor roll between the fountain roll and form roll, and a driving member having a ratchet connection with the fountain roll and a frictional slip connection with the ductor roll.

8. In a planographic printing machine, the combination of a plate cylinder, a form roll adapted to coast therewith, a fountain roll, a bodily shiftable and rotatable ductor roll between the fountain roll and form roll, a reciprocating bar having a frictional slip connection with the ductor roll, a ratchet drive for the fountain roll connected with said bar, and means for reciprocating the bar.

9. In a planographic printing machine, in combination with the plate cylinder of a repellent applicator and an ink applicator, each applicator comprising a form roll, a fountain roll and an intermediate bodily removable ductor roll, rat-

5 chets on the respective fountain rolls, two reciprocating bars having frictional slip connections with the two ductor rolls respectively, means whereby each bar may operate the ratchet of the corresponding fountain roll, and common driving mechanism so connected with the bars so that it may simultaneously move them to operate the two fountain rolls and the two ductor rolls.

10. The combination of a fountain roll, a receiving roll parallel therewith and spaced therefrom, and a bodily movable and rotatable ductor roll between the fountain roll and receiving roll and mechanism adapted to perform the double function of giving a partial rotation to the fountain roll and also of shifting the ductor roll into engagement with one of the said other rolls and there retaining it without increasing its pressure against the roll it engages.

11. The combination with a rotatable fountain roll and a bodily movable and rotatable ductor roll, a single operating mechanism adapted to move the ductor roll into contact with the fountain roll and retain it there without increase of its pressure thereagainst while the same mechanism gives a periodic rotation of the fountain roll.

12. The combination of a fountain roll, a roll parallel therewith and spaced therefrom, and a bodily movable and rotatable ductor roll between the fountain roll and parallel roll, and reciprocating mechanism adapted on one stroke to shift the ductor roll into engagement with one of the other rolls and retain it there without increase of its pressure thereagainst and on the opposite stroke to give a partial rotation to the fountain roll.

13. The combination with a fountain roll having a ratchet wheel, and an ink receiving roll, of an interposed ductor roll, mechanism for moving the ductor roll into contact with the ink receiving roll and there holding it for an appreciable time and at a constant pressure and during that time continuing the movement of said mechanism, and a pawl for operating the ratchet moved in the idle direction by said continuing movement.

14. In a planographic printing machine, hav-

ing a plate cylinder, an ink feed for the plate cylinder, a repellent feed for the plate cylinder, each of said feeds including a movable ductor roll and a ratchet driven fountain roll, means for moving the ductors, and means for causing the ductors to dwell in engagement with the members against which they are moved while the moving mechanism continues its movement to actuate mechanism coacting with the ratchets.

15. In a planographic printing machine, having a plate cylinder, an ink feed for the plate cylinder, a repellent feed for the plate cylinder, each of said feeds including a movable ductor, means for moving the ductors, said means including members which have both a shoving and a sliding action on the ductor supports to permit the ductors to dwell in engagement with the members against which they are moved while the moving mechanism continues its movement.

16. In a planographic printing machine, having a plate cylinder, and an offset cylinder, an ink feed for the plate cylinder, a repellent feed for the plate cylinder, each of said feeds including a fountain roll and a movable ductor, a moving mechanism operated by the offset cylinder, shoving and sliding connections between said driving means and the ductors for causing the ductors to dwell in engagement with the members against which they are moved while the moving mechanism continues its movement, and reciprocating mechanism for turning the fountain rolls actuated in one direction by said movement.

17. The combination, with a rotatable movable fountain roll and a bodily movable ductor roll, of a single driver for both movements, and mechanism connecting the driver with the two rolls, said mechanism having a connection with the ductor roll which is capable of moving the ductor roll a predetermined distance only and then is active to maintain the ductor roll in such position without increasing the pressure between the ductor roll and fountain roll, whereby the ductor roll may dwell at one end of its movement while the mechanism continues to operate the fountain roll.

FRANKLIN E. CURTIS.
